UNITED STATES PATENT OFFICE.

THOMAS B. GIBSON, OF GLASGOW, COUNTY OF LANARK, SCOTLAND.

ORNAMENTAL VESSEL OR ARTICLE.

SPECIFICATION forming part of Letters Patent No. 404,785, dated June 4, 1889.

Application filed June 8, 1888. Serial No. 276,536. (No model.)

To all whom it may concern:

Be it known that I, THOMAS BOWE GIBSON, a subject of the Queen of Great Britain and Ireland, and a resident of Glasgow, in the 5 county of Lanark, Scotland, have invented certain Improvements in Ornamental Vessels or Articles, of which the following is a specification.

This invention relates to certain improvements in the manufacture and ornamentation of vessels or receptacles—such as jars, so-called “specimen-glasses,” and the like—to imitate earthenware, china, porcelain, terracotta, and such like, the object being to combine with a foundation or body substance woven fabrics which will be laid onto or can adhere or be drawn over the articles formed from the body or foundation material.

In the accompanying drawings I have illustrated some examples of vessels in which my invention is embodied; but I do not wish to restrict myself to any special style or form of the vessel or article to be ornamented.

Figure 1 is a perspective view of a vessel—25 an umbrella-jar, for instance—to be ornamented. Fig. 2 is an enlarged view of a piece of fabric to be employed in the decoration; and Fig. 3 is a view of the vessel, Fig. 1, as ornamented.

30 The invention is carried out as follows: The foundation or body giving the form of the article or vessel, Fig. 1, may be made of “papier-maché” or straw-board, earthenware, stiffened felt, linoleum, corticine, linerusta, 35 oil-cloth, kamptulicon, and such like substances stiffened to form the article, or the body may be formed of thin metal or wood, plain or perforated.

30 The woven or knitted fabrics employed to 40 cover the article or vessel may be of cotton or wool or silk, or be mixed fabrics or unions—such as cotton and wool, or silk and wool, or cotton and silk—whether plain or knitted or figured—or of lace or net fabric, such as indicated in Fig. 2.

45 The woven or knitted fabrics are of open-work, and are laid onto the body or stretched over the body of the vessel which is colored or ornamented, so that the coloring or pattern 50 will be disclosed through the texture of the fabric, which may itself be ornamented or

carry a pattern *b*, Fig. 2, to combine with the body pattern or coloring, and these fabrics may be of varying textile combinations.

The applied fabrics of heavy texture will 55 themselves be ornamented in color or pattern previously to their being applied to the body. The body of the article may also be formed from a material, such as linoleum, and so forth, oil-cloth or carpet, with jute or linen back 60 stiffened for the purpose, and the ornamentation can be produced by printing, staining, or by being woven thereupon before the formation of the article.

The fabric pieces may also be produced and 65 sold as slips—that is, “sleeves”—of material, which may be then applied as decoration to existing bodies.

In the decoration of the fabrics the same 70 designs may be formed by weaving, embroidery, tambouring, braiding, or any other ornamentation produced by machine or hand work, or it may be produced by printing or by stamping, impressing, or flocking, or by painting by hand or otherwise a combination 75 of these.

The surfaces may be finished by the application of a hard-setting varnish or otherwise.

I claim as my invention—

1. An ornamental vessel or article consisting of the combination of a foundation or body substance with a woven-fabric covering of open-work stretched over the foundation and showing the color or ornamentation of the latter, substantially as and for the purpose 85 herein set forth.

2. An ornamental vessel or article consisting of the combination of a foundation or body substance with a woven-fabric covering of open-work carrying a design or ornamentation and stretched over the foundation, but showing through it the color of the latter, substantially as and for the purpose herein set forth.

In testimony whereof I have signed my name 95 to this specification in the presence of two subscribing witnesses.

T. B. GIBSON.
